(57) **CLAIM**

The ornamental design for a table lamp, as shown and described.

DESCRIPTION

FIG. 1 is a bottom, front and right side perspective view of a table lamp showing my new design;
FIG. 2 is a top, rear and left side perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of portion 9 in FIG. 4;
FIG. 10 is an enlarged view of portion 10 in FIG. 4; and,
FIG. 11 is an enlarged view of portion 11 in FIG. 7.
The table lamp is shown with symbolic breaks in its length.
The appearance of any portion of the article between the
break lines forms no part of the claimed design.

1 Claim, 11 Drawing Sheets
